UNITED STATES PATENT OFFICE.

GUY P. SLATER, OF TULSA, OKLAHOMA.

WALKING BEAM FOR OIL WELLS AND THE LIKE.

Application filed August 7, 1924. Serial No. 730,742.

To all whom it may concern:

Be it known that I, GUY P. SLATER, a citizen of the United States of America, and resident of Tulsa, in the county of Tulsa and State of Oklahoma, have invented certain new and useful Improvements in Walking Beams for Oil Wells and the like, of which the following is a specification.

This invention relates to machine elements 10 and particularly to walking beams.

It is an object of this invention to produce a walking beam with parts associated with it having a capacity for absorbing shocks and vibrations, due to the use of the 15 walking beam in connection with pumps for oil wells and the like.

It is well known that walking beams for such use, especially in very deep wells are subjected to considerable strain and it is an 20 object of this invention to associate with the said walking beam, novel means for relieving the apparatus and the pump from undue strain and vibration.

It is a further object of this invention 25 to produce a walking beam having a truss or base extending from the center toward each end and to provide novel means for adjustably anchoring the truss in order that compensation may be attained for taking up 30 lost motion and the like.

It is a further object of this invention to provide anchorages at the ends of the beams for the pitman stirrup and temper screw and a central trunnion and coupling 35 whereby the trunnion is secured to the beam.

With the foregoing and other objects in view, the invention consists in the details of construction and in the arrangement and combination of parts to be hereinafter more 40 fully set forth and claimed.

In describing the invention in detail, reference will be had to the accompanying drawing forming part of this application, wherein like characters denote corresponding 45 parts in the several views and in which—

Figure 1 illustrates a top plan view of a walking beam embodying the invention;

Figure 2 illustrates a side elevation 50 thereof;

Figure 3 illustrates a view in elevation of a pitman stirrup;

Figure 4 illustrates an enlarged detail 55 view of the end of the walking beam on which the pitman stirrup is mounted; and

Figure 5 illustrates a sectional view of the pitman stirrup box.

In these drawings, the beam is shown as being formed of a plurality of parts including sides 10 and 11 comprising channel 60 plates which are in spaced relation to each other and the space therebetween is covered by a top plate 12 secured to the flanges of the channel plates by fastenings 13, such as rivets or the like.

A bottom plate 14 similar to the plate 12 is secured to the bottom flanges of the channel plates. The top plate and bottom plate have apertures 15 and 16 on each side of the center of the beam through which truss 70 rods 17 project, it being shown that each truss rod extends diagonally through the beam from the top to bottom and that the adjoining ends of the truss rods are connected by a link 18, although other means 75 may be resorted to for connecting the truss rods or, under certain conditions, a continuous rod may be employed.

The outer ends of the truss rods are threaded as at 19 to be engaged by nuts 80 20 in order that the tension of the truss rods may be increased or diminished to suit particular requirements. The rods extend through blocks 21 that are secured to the beam and each block has a diagonally disposed aperture 22 through which an end of one of the truss rods extends. Preferably, the truss rods are held in spaced relation to the upper plate of the beam by I-beams 23 that extend across the top of the 85 beam and rest thereon. A trunnion 24 for the I-beam, in the present embodiment of the invention, extends across the top of the I-beam in engagement therewith and it is drawn into engagement with the beam by 90 clips or yokes 25 comprising one or more U-shaped bolts whose looped portion or portions embrace the trunnion and whose ends extend through a plate 26 bearing against the bottom plate of the beam. The parts 95 are held in the assembled relation just described by fastenings 27 such as nuts which are threaded on the bolts as shown.

The bearing 28 for the head of the temper screw which is, of course, of ordinary construction, may be attached to the beam by fastenings 29 such as rivets, bolts or the like and the opposite end of said beam is provided with a pitman strap bearing or box.

In the present embodiment of the inven-

tion the pitman strap 30 has its lower end or head lying in a seat 31 of the box or bearing 32 and it is held in place by a half box or bearing 33 that is secured in place by 5 fastenings 34 in the end by bolts, or the like, which bind the parts together as will presently appear.

The under surface of the bearing block 32 is recessed to form a cavity 35 and depending side flanges 36 which embrace a yieldable cushion 37 so as to confine the said cushion in the cavity between the bottom of the bearing and a base block 38, preferably of cast iron or the like, which rests on the 15 upper surface of the beam. The fastenings 34 preferably extend through the cushion and the baseblock so that these are anchored to the beam with the bearing for the pitman strap as is quite well shown in Figure 20 5. The presence of the cushion will permit certain yielding action of the bearing 32 according to the resiliency or yielding character of the cushion and it will be understood that the cushion may be of increased 25 or diminished thickness and yielding properties, according to the requirements in practice as to the load that the beam must carry and the like.

It will be seen from an inspection of the 30 drawing that the flanges 26 are of such depth as to embrace the cushion and partially the sides of the base block, but there is a clearance between the flanges and the beam to permit movement of the bearing 35 with relation to the base block and beam. This relation of parts insures proper guiding of the bearing and aids in retaining the parts in their assembled relation.

It will also be apparent from an inspection 40 of the drawing, that the tension of the trusses may be increased or diminished and that a comparatively strong beam may be constructed from material of comparatively light gage and changes of course may also

be made in the details of construction without departing from the spirit of the invention within the scope of the appended claims.

I claim:

1. A walking beam for well drilling and 50 pumping comprising side channel plates, a top plate and a bottom plate above and below the flanges secured thereto, I-beams extending transversely of the top plate on each side of the trunnion of the walking 55 beam, truss rods supported on the I-beams and having their ends connected together between the I-beams, the top and bottom plates of the walking beam having diagonally disposed apertures through which the truss rods extend, and means on the outer ends of the truss rods for anchoring the same to the lower plate of the walking beam.

2. A walking beam for well drilling and 55 pumping comprising side channel plates, a top plate and a bottom plate above and below the flanges secured thereto, I-beams extending transversely of the top plate on each side of the trunnion of the walking beam, a yoke comprising U-shaped bolts inverted 70 with respect to the walking beam and having their ends projecting through the top and bottom plates of the walking beam, a trunnion resting on the upper plate of the walking beam and 75 extending transversely thereof through the loop of the yoke whereby the trunnion is anchored on the walking beam, truss rods supported on the I-beams and having their ends connected together between the I- 80 beams, the top and bottom plates of the walking beam having diagonally disposed apertures through which the truss rods extend, and means on the outer ends of the truss rods for anchoring the same to the 85 lower plate of the walking beam.

GUY P. SLATER.
